UNITED STATES PATENT OFFICE.

JOSEPH NEMSER, OF NEW YORK, N. Y., ASSIGNOR TO NEMSER GOWNS, INC., OF NEW YORK, N. Y., A CORPORATION OF NEW YORK.

DESIGN FOR A GOWN.

Application filed June 23, 1922. Serial No. 2,798. Term of patent 3½ years.

To all whom it may concern:

Be it known that I, JOSEPH NEMSER, a citizen of the United States of America, residing at New York city, county and State of New York, have invented a new, original, and ornamental Design for a Gown, of which the following is a specification, reference being had to the accompanying drawing, forming part hereof, in which the figure is a front view of a gown showing my new design.

I claim:

The ornamental design for a gown, as shown.

JOSEPH NEMSER.
